(57) **CLAIM**

We claim the ornamental design for a nozzle, as shown and described.

DESCRIPTION

FIG. 1 is a side elevation view of a first embodiment of the nozzle,

FIG. 2 is a bottom side perspective view of the nozzle of FIG. 1,

FIG. 3 is a top side perspective view of the nozzle of FIG. 1,

FIG. 4 is a top view of the nozzle of FIG. 1, and

FIG. 5 is a bottom view of the nozzle of FIG. 1.

FIG. 6 is a side elevation view of a second embodiment of the nozzle,

FIG. 7 is a bottom side perspective view of the nozzle of FIG. 6,

FIG. 8 is a top side perspective view of the nozzle of FIG. 6,

FIG. 9 is a top view of the nozzle of FIG. 6, and

FIG. 10 is a bottom view of the nozzle of FIG. 6.

FIG. 11 is a side elevation view of a third embodiment of the nozzle,

FIG. 12 is a bottom side perspective view of the nozzle of FIG. 11,

FIG. 13 is a top side perspective view of the nozzle of FIG. 11,

FIG. 14 is a top view of the nozzle of FIG. 11; and,

FIG. 15 is a bottom view of the nozzle of FIG. 11.

All broken lines illustrate portions of the nozzle to which the design is applied that form no part of the claim.
